WATCHMAN'S CLOCK

Filed Dec. 4, 1922

2 Sheets-Sheet 2

UNITED STATES PATENT OFFICE.

OTTO E. HAUSBURG, OF BROOKLYN, NEW YORK.

WATCHMAN'S CLOCK.

Application filed December 4, 1922. Serial No. 604,688.

To all whom it may concern:

Be it known that I, OTTO E. HAUSBURG, a citizen of Germany, residing at Brooklyn, in the county of Kings and State of New York, 5 have invented certain new and useful Improvements in Watchmen's Clocks; and I do hereby declare the following to be a full, clear, and exact description of the invention, such as will enable others skilled in the art 10 to which it appertains to make and use the same, reference being had to the accompanying drawings, and to characters of reference marked thereon, which form a part of this specification.

15 This invention relates, generally, to improvements in portable watchmen's clocks used to control and report the movement of watchmen; and the invention has reference, more particularly, to various improved features 20 relating to the key controlled recording mechanism of such clocks.

The invention has for its principal objects to provide improvements in the key controlled means for actuating the recording 25 mechanism; and in means for rendering an audible signal denoting the proper cooperative actuation of key and recording mechanism; and in other improved details as will subsequently appear.

30 The invention is clearly illustrated in the accompanying drawings, in which:—

Figure 1 is a rear face view of the novel construction of watchmen's clock, with the hinged cover member thereof partly broken away; Figure 2 is a front face view of said watchman's clock; Figure 3 is an interior view of the clock casing, with the hinged cover member removed, to show the novel means for supporting the clock movement 35 within said case; Figure 4 is a vertical section of the case, with the clock movement therein shown in elevation; Figure 5 is a transverse vertical section through the case, taken on line 5—5 in Figure 4, with the 40 clock movement and recording mechanism shown in elevation, said view being drawn on an enlarged scale; Figure 6 is a part side elevation and part vertical longitudinal section taken on line 6—6 in Figure 5; Figure 45 7 is a transverse section, taken on line 7—7 in Figure 5; Figure 8 is a view similar to that shown in Figure 7, but illustrating a station key inserted and turned to actuate the recording mechanism; and Figure 9 is a 50 perspective view of the key actuated key-barrel locking device.

Similar characters of reference are employed in all of the hereinabove described views, to indicate corresponding parts.

Referring now to said drawings, the reference character 1 indicates a casing providing an interior enclosure within which the movement and recording mechanism of the clock is mounted. The open back of said casing is normally closed by a hinged 60 cover 2; the casing and cover having mutually cooperating means for locking the latter in closed relation to the former. The front wall of said casing is provided with an aperture 3 beneath which the clock-dial 4 of the 65 movement is alined, when the movement is mounted in said casing. Suitably secured across said aperture is a transparent glass or crystal 5. Surrounding said aperture 3, so as to project outwardly from the face of the casing wall, is an annular rim or flange 6, the outer sides of which are undercut to provide the annular groove 7. A protector device or guard plate 8, the body of which is suitably perforated with openings 9 to permit 70 a view of the underlying dial 4, is provided in rearward projection from its periphery with integral spring fingers or tongues 10 which spring over the free edges of the rim or flange 6 and into the groove 7, to thereby 75 attach the protector device or guard-plate 8 in place. The said protector device or guard-plate 8, serves to guard the glass or crystal 5 against blows, whereby the same 80 might be cracked or broken.

90 The movement and operative parts of the clock are mounted upon a base-plate 11, the clock movement per se being enclosed in a secondary casing or cover shell 12, upon the upper side of which is fixed the dial 4, and 95 through which projects the spindle for actuating the clock-hand 13, which cooperates with said dial. Fixed upon said base-plate 11, below the clock movement, is a transverse bracket plate 14. Also mounted on said base-plate 11, opposite to and spaced from said bracket-plate 14, is a block 15, the same having a keyhole opening or passage 16 of proper shape to permit the passage therethrough of the station or operating keys 17 provided for actuating the recording mechanism of the 100 clock. Journalized by its respective ends in said bracket plate 14 and said block 15, so as to extend between the latter parts, is a 105 rotary key-barrel 18 provided with a longitudinal bore 19 to receive the stem 20 of a 110

key 17, and with a longitudinal slot 21 to permit the movement of the bit 22 of the key 17 into the barrel so that said bit may project laterally from the barrel when the key is thus inserted. Said key-barrel 18 is provided, adjacent to its inner end, with an annular flange 23 which lies against the outer side of the bracket-plate 14. Supported between said bracket-plate 14 and said block 15 is a shaft or spindle 24 upon which are pivotally mounted, side by side, a series of recording levers 25, which are each provided at their under sides with downwardly projecting extensions 26, the free ends of which extend through an opening in the base-plate 11 so as to be engageable with the removable paper record dial 27 which is actuated by the clock-movement in the usual manner. The free end of each recording lever extension 26 is provided with a male embossing die 28 corresponding to the particular station represented thereby. Each recording lever 25 is further provided at its free end with an upwardly turned portion 29, from the rearward side of which projects a lift lug 30. Said key-barrel 18 is provided along its side with a longitudinal stop lip or flange 31, which, when said key-barrel occupies its normal initial position, engages said lift lugs 30 of the several recording levers 25 to thereby normally lock the latter in raised position and held against operation until the key-barrel is released and rotated by a proper station key, thus providing a very simple and direct interlocking of recording levers and key-barrel which is one of the novel features of this invention. In order to prevent rotation of the key-barrel 18, and consequent release of the recording levers for operation, except by a proper station key, I provide a novel means for normally locking said key-barrel against rotation, such locking means being releasable only by the insertion into the key-barrel of a key possessing the proper height and length of bit. This locking means comprises a flat spring member 32, which is secured by one end to the inner side of said bracket-plate 14. Said spring member 32 is provided adjacent to its free end with a push-tongue 33 which projects outwardly at a right angle therefrom through a suitable opening in said bracket-plate 14, so as to lie in the path of key bit when the said key is inserted into the key-barrel. Said spring member 32 is further provided, adjacent to its free end with a laterally projecting stop-pin 34, which also projects through an opening provided therefor in said bracket plate 14 so as to normally enter a notch or slot 35 provided in the periphery of the flange 23 of the key-barrel 18 whereby the latter is locked against operative rotation. When a proper key, having the correct bit dimen-

sions, is inserted into the key-barrel 18, the inward movement thereof carries the end of the bit 22 against the end of said push-tongue 33, which is thereupon pressed inward thus flexing the spring member 32 whereby said stop-pin 34 is retracted from the notch or slot 35, thus freeing the key-barrel for operative rotation. It will be evident that the key bit 22 must be of proper dimensions in order that its insertion will actuate the spring member and associated parts to release the key-barrel 18 for rotation, and consequently the key barrel is so locked in normal initial position as to render tampering with the recording mechanism by means of a false or improper key exceedingly difficult, while at the same time the locking of the key-barrel in normal initial position also holds the recording levers secure against improper operative depression because of the mutual engagement of the stop lip or flange 31 with lift lugs 30 of said recording levers. Another novel feature associated with the key controlled recording mechanism of the clock comprises a signal device which is adapted to give an audible sound or click when the key has been fully turned to actuating relation to a recording lever. This device is adapted to readily assure the watchman that he has turned the actuating key with sufficient pressure to produce the necessary cooperation of the male die 28 with a female die block 36 to the end that a proper embossing of the station number on the paper record dial 27 has been accomplished, and a sufficiently definite indication of his visit to the given station has been duly impressed upon the said record dial 27. This signal device comprises a pivoted click block 37 mounted upon an outwardly projecting fulcrum pin 38, fixed to said bracket plate 14, so that its free end extends toward the flange 23 of the key-barrel 18. Secured to the free end of said click block 37, so as to project longitudinally outward therefrom, is a spring finger 39. Said click-block is actuated to swing down upon a sounding post 40, by means of a pull spring 41. Fixed to said annular flange 23 of said key-barrel 18 is a trip-pin 42. When said key-barrel 18 is released and rotated by a proper station key, the rotation of the flange 23 will carry upwardly the trip-pin 42 which will engage the end of the spring finger 39 and will lift or swing upward the click-block 37 (as shown by the full lines in Figure 8). As the key is turned to the proper limit of its recording lever actuating movement so that a proper registering of the station number is produced upon the record dial 27, the trip-pin 42 will escape from the end of the spring finger 39, so that the spring 41 will snap down the click block 37 smartly against the sounding post 40.

(as indicated by the dotted lines in Figure 8), thereby producing a sharp and clearly audible "click" or signal sound for the purposes above referred to. When the key-barrel 18 is rotated back to normal initial position, the trip-pin 42 will engage the upper side of spring-finger 39 which is sufficiently flexible to yield to the backward passage of said trip-pin, so that the latter is permitted to resume normal initial position.

I am aware that some changes may be made in the various arrangements and combinations of the several devices and parts and in the features of my present invention without departing from the scope thereof as described in the foregoing specification, and as defined in the claims appended hereto. Hence, I do not limit my invention to the exact arrangements and combinations of the various devices and parts as hereinabove set forth, and as illustrated in the accompanying drawings, nor do I confine myself to the exact details of the construction of the said parts.

I claim:

1. In a watchmen's clock, the combination with pivoted recording levers of a rotary key-barrel having means for raising and holding said recording levers in a normal initial position of rest.

2. In a watchmen's clock, the combination with pivoted recording levers of a rotary key-barrel, a longitudinal laterally projecting stop-lip on said key-barrel, and said recording levers having at their free ends lift-lugs projecting toward said key-barrel so as to be engageable by said stop-lip whereby the latter may raise and hold said recording levers in a normal initial position of rest.

3. In a watchmen's clock, the combination with pivoted recording levers of a rotary key-barrel having means for raising and holding said recording levers in a normal initial position of rest, and means releasable by the insertion of a proper key into said key barrel for normally locking said key-barrel in initial position against rotation.

4. In a watchmen's clock, the combination with pivoted recording levers of a rotary key-barrel, a longitudinal laterally projecting stop-lip on said key-barrel, said recording levers having at their free ends lift-lugs projecting toward said key-barrel so as to be engageable by said stop-lip whereby the latter may raise and hold said recording levers in a normal initial position of rest, and means releasable by the insertion of a proper key into said key barrel for normally locking said key-barrel in initial position against rotation.

5. In recording mechanism for watchmen's clocks, the combination with a rotary key-barrel and a stationary bracket plate in which the rear end of said key-barrel is jour-

naled, of a key actuated releasable means for normally locking the key-barrel against rotation, comprising an annular flange at the inner end of said key-barrel having a notch in its periphery, a spring plate fixed at one end to said bracket plate, a push-finger connected with said spring plate adjacent to its free end to project longitudinally forward into the path of a key entering said key-barrel, and a stud also connected with said spring plate adjacent to its free end to normally enter said notch of said annular flange of the key-barrel, said bracket plate having openings through which said push finger and said stud project.

6. In a watchmen's clock, the combination with pivoted recording levers of a rotary key-barrel having means for raising and holding said recording levers in a normal initial position of rest, and a key actuated releasable means for normally locking the key-barrel against rotation, comprising an annular flange at the inner end of said key-barrel having a notch in its periphery, a spring plate fixed at one end, a push-finger connected with said spring plate adjacent to its free end to project longitudinally into the path of a key entering said key-barrel, and a stud also connected with said spring plate adjacent to its free end to normally enter said notch of said annular flange of the key-barrel.

7. In a watchmen's clock, the combination with pivoted recording levers of a rotary key-barrel, a longitudinal laterally projecting stop-lip on said key-barrel, said recording levers having at their free ends lift lugs projecting toward said key-barrel so as to be engageable by said stop-lip whereby the latter may raise and hold said recording levers in a normal initial position of rest, and a key actuated releasable means for normally locking the key-barrel against rotation, comprising an annular flange at the inner end of said key-barrel having a notch in its periphery, a spring plate fixed at one end, a push-finger connected with said spring-plate adjacent to its free end to project longitudinally into the path of a key entering said key-barrel, and a stud also connected with said spring plate adjacent to its free end to normally enter said notch of said annular flange of the key-barrel.

8. In a recording mechanism for watchmen's clocks, a rotary key-barrel to receive an actuating key, a signal means for producing an audible signal when the key and key-barrel have been turned to complete the operative actuation of the recording mechanism, and a trip means on said key-barrel for operating said signal means.

9. In a watchmen's clock, the combination with pivoted recording levers of a rotary key-barrel having means for raising and holding said recording levers in a normal

- initial position of rest, means releasable by the insertion of a proper key into said key-barrel for normally locking said key-barrel in initial position against rotation, a signal means for producing an audible signal when the key and key-barrel have been turned to complete the operative actuation of the recording levers, and a trip means on said key-barrel for operating said signal means.
10. 10. In a recording mechanism for watchmen's clocks, a rotary key-barrel to receive an actuating key, a pivoted spring controlled click block, a fixed sounding post engageable by said click block, a trip means on said key-barrel for actuating said click block
- 15

upon the completion of the rotation of said key-barrel in operative direction, and yieldable means of said click block permitting the return of said trip means to normal initial position beneath said click block when said key-barrel is turned back to normal initial position.

In testimony, that I claim the invention set forth above I have hereunto set my hand this 3rd day of November, 1922.

OTTO E. HAUSBURG.
